DARNING MACHINE

Erik Gustaf Ahnström, Stake, Sweden

Application September 5, 1941, Serial No. 409,747
In Sweden July 14, 1939

8 Claims. (Cl. 66—2)

The present invention relates to darning-machines of the type having reciprocating knitting needles.

A feature of the invention consists in that the machine comprises a member which by its rotation reciprocates the knitting needles.

Other features of the invention are described in the following specification with reference to the drawings which by way of example illustrate a preferred embodiment of the invention.

In the drawings,

Figs. 1 and 2 are perspective views of the machine in open and closed positions respectively.

Fig. 3 is an enlarged scale vertical section of the machine.

Fig. 4 is another vertical section on the line IV—IV in Fig. 3.

Figs. 5 to 10 show several details of the machine.

The machine comprises a case 1 adapted to be secured on a table or the like by means of a hand screw 2.

A number of knitting or stitching needles 3 are vertically slidable, each being moved up and down by means of an angle lever 4 which is mounted at the lower part of the case 1 to swing about a shaft 5, and by a vertical rod or bar 6 the lower end of which is connected to the lever 4 and the upper end of which is connected to the needle 3. Each lever 4 is given a rocking movement by means of a drum 7 which is rotatably mounted in the case 1 and is provided at its circumference with two cams 8 and 9 provided with a stage for each lever. The stages of said cams 8 and 9 are adapted to cooperate with the two noses 10 and 11 on each lever 4 in such manner that after the last stage on the cam 8 has left the nose 10 of the associated lever 4, the nose 11 of the first lever 4 is engaged by the first stage on the cam 9. The drum 7 which is mounted to rotate on a shaft 12 is provided with teeth 13 on its circumference, said teeth meshing with a gear wheel 14 secured on a shaft 15 which is rotatably mounted in the case 1. On the end of said shaft 15 extending outside the case 1 a crank 16 is secured, which preferably is adapted to be rotated in only one direction. By the rotation of the drum 7 in the direction of the arrow A, i. e. clockwise as viewed in Fig. 3, by means of the crank 16 the stages on each of the cams 8 and 9 actuate the associated levers 4 and by means of the associated bars 6 also the associated needles 3, each of which at first is raised, for instance, by the cam 9 contacting the nose 11, and thereafter is lowered by the same cam contacting

the nose 10 of the associated lever 4. For the needles 3 apertures 17 are provided in a horizontal wall 18 of the case 1, said wall being the top of an upward extension of the front part of the case 1. This horizontal wall 18 forms a support for the fabric as described in the following.

For feeding the fabric a feeder is provided which consists of a number of feeding needles 19 secured in a frame 20 which is rotatably mounted on a shaft 21. Said shaft 21 is held between curved claws 22 (Fig. 8) projecting from a plate 23 which is supported by a frame 24 and is connected with the same by a spring 25 having its one end secured to the plate 23 and its other end to a shaft 26 in the case 1. This shaft 26 together with pins 27 secured in the case 1 form guiding means for the vertical movement of the frame 24, the shaft 26 and the pins 27 being slidable in guides 28 in the side walls of the frame 24. The bottom part 29 of the frame 24 is adapted to cooperate with a disc 30 (Fig. 3) which is secured on the drum 7 and is provided in its circumference with two diametrically disposed recesses 31, the bottom part 29 of the frame 24 by action of the spring 25 periodically engaging each of said recesses at the rotation of the drum 7, so that the frame is periodically lowered. Said recesses 31 are so disposed that the frame 24 is lowered when all the stitching needles 3 take their lowermost position. The side parts 32 of the frame 20 engage with a guide 33 secured on the case 1, said guide having such a shape that the frame 20 and thereby also the feeding needles 19 are given the motion illustrated by the lines B in Fig. 8. In the lowered position of the feeding needles 19 their points are positioned below the upper surface of the horizontal wall 18 in order to permit the insertion of the fabric and its periodic feeding. At their upward movement the feeding needles 19 penetrate the fabric and cause by their inward movement the feeding of the fabric.

Each stitching needle 3 is provided with a hook 34, which at the downward movement of the needle catches the thread 35 (the yarn) as described in the following. As in known stitching machines each stitching needle according to the embodiment illustrated in Fig. 9 is provided with a slide 36 which is slidable in the needle and at the downward motion of the needle by action of a spring 37 secured to the case 1 is brought to overlap the hook 34. Thereby the thread 35 is permitted to be drawn through the fabric or through a stitch already formed. Interposed plates 38 secured to the case 1 serve to guide the stitching

needles 3 and the bars laterally. On the outer side of the case 1 a spindle 39 is secured on which a bobbin 49 for the thread 35 is arranged which runs from the bobbin 40 through an eye 41 formed in a wire spring 42, and to another eye 43 secured on the thread guide 44. The thread is held at a suitable tension by the action of the spring 42. The thread guide 44 consists of a bar which is rockably mounted on a vertical shaft 45 secured in the hollow arm 46. The rear end of the bar 44 is bent downwards (Fig. 4) and engages in the forked end 47 of a bar 48 which is rockably mounted on a horizontal shaft 49 secured in the case. The lower part of the bar 48 is bent substantially at a right angle and is provided with a forked end 50 (Fig. 4) engaging the edge of a cam disc 51 which is secured to the drum 7 and arranged to give the bar 48 an oscillating movement at the rotation of the drum 7. By this oscillation of the arm 44 and of the eye 43 the thread is moved in front of all the stitching needles 3 so that they catch the thread at their downward movement. The hollow arm 46 is rockable about a horizontal shaft 52 in the case 1 so that the arm 46 may be opened as shown in Fig. 1 for insertion of the fabric. In the part of the arm 46 over the part 18 of the case 1 a member 53 of "Bakelite" or the like is secured which is provided with a downwardly projecting part with grooves 54, the front side of said member 53 being arranged to guide the stitching needles 3 in their raised position. In the aperture 17 a grate 55 is provided which consists of parallel bars each located between two adjacent stitching needles 3. At the downward movement of the stitching needles 3 certain parts of the thread are retained resting on the grate bars, so that the parts of the thread which are drawn down by the needles 3 form a number of loops 56 (Fig. 10) corresponding to the spaces between the bars. The downward movement of the needles 3 should begin at that side on which the thread is attached to the fabric, i. e. at the side opposite to the eye 43 of the thread guide.

A disc 57 is secured on the drum 7, the edge of side disc being provided with a notch 58, in which a pawl 59 is adapted to engage by the action of a spring 60. This pawl 59 is connected by a link 62 with an arm 63 rockably mounted on the outer side of the case, so that the pawl 59, by the rocking of the arm 63 and stretching the spring 60, is forced into engagement with the notch 58 thereby locking the drum 7 against movement. The position of the notch 58 is such that the pawl 59 engages in the same when the needles are in their lowermost or substantially lowermost position. The pawl 59 is firmly connected by an arm 64 with a sector-shaped indicating disc 65, which through a window 66 in the case shows the position of the pawl and thus indicates whether the drum 7 is locked or released. The arm 63 may be connected by a linkage (not shown) with the arm 46 in such manner that said arm 46 is free to be turned upward only when the pawl 59 engages in the notch 58 whereby the rotation of the drum 7 is prevented when the needles 3 take their lowest position in which the fabric may be inserted or withdrawn.

The machine is provided with means for altering the width of the stitches in order that the darn may be given a similar appearance to the other part of the fabric. The variation of the width of the stitches implies that the stitches 56 formed by the stitching needles (Fig. 10) are altered regarding their length below the grate bars

55. Thus, the lowest position of the stitching needles 3 may be altered, and since the movement of these needles is performed by means of the levers 4 the said regulation is dependent on the extent of the movement of these levers. Said movement may, of course, be altered in several ways, and the illustrated embodiment shows one way. As above described the levers 4 are turnable about the shaft 5. According to the embodiment illustrated (see especially Fig. 3) the ends of the shaft 5 are provided with eccentric journals 67, both journals being rotatably mounted in the case 1. A handle 68 is secured on one of the journals 67 by which handle the shaft 5 may be rotated. By this rotation that portion of the shaft, on which the levers are mounted, may be raised or lowered, whereby the position of their common axis is altered relatively to the shaft 12, so that the engagement of the cams 8 and 9 with the nose 10 is altered, whereby the levers 4 are given a larger or smaller turning movement. The vertical alteration of the position of the axis of turning of the levers 4 has, on the contrary, no influence on the operation of the cams 8 and 9 on the nose 11, since this nose is positioned approximately vertically above the shaft 5. Suitably the two arms of the levers 4, which are provided with the noses 10 and 11, form approximately a right angle to each other.

30 The width of the stitches may be indicated in several ways. Fig. 7 shows a suitable device for such indication. This device consists of a disc 69 secured on the journal 67, which disc is provided with a concentric band 70 tapered in one direction and visible through a window 71 in the case 1. If the disc 69 is rotated, for instance clockwise, by means of the handle 68, the width of the band portion visible in the window 71 and indicating the stitch width is decreased.

40 The stitching needles 3 are arranged in a row perpendicularly to the feeding direction of the fabric. Consequently the length of the row of the operating needles 3 determines the width of the darn. Thus, in order to decrease the width 45 of the darn said row shall be shortened, which is done by putting a certain number of needles at each end of the row out of operation. For this purpose a segmentary member 73 is secured on a shaft 12 rotatably mounted in the case, said member 73 at one edge being provided with stages (Fig. 6), which at the rotation of the shaft 12 and thus of the member 73 act upon groups 50 of the bars 6, so that the lower ends of said bars engaging in an aperture 74 in the levers 4 are released, whereby the corresponding stitching needles 3 are put out of operation. An arm 75 (Fig. 5) is secured on one end of the shaft 12 outside of the case 1, the turning of said arm being limited in both directions by stops 76 on the outside of the case. The case is provided with indicating lines 77 having different length, which, depending upon the position of the arm 75 opposite one or the other row directly shows the width of the darn. To support the released rods 6 a bar 78 is secured in the case, which bar in released position of the rods 6 is engaged by a bent portion of the same so that the rods are locked (compare the dotted line in Fig. 3). Suitably the connection of the shaft 12 or the member 73 with the hook 59 or its operating member is such that alteration of the width of the darn is permitted only when the hook 59 engages in the disc 57, i. e. when the drum is locked.

70 The front side of the case 1 is provided with a door 79 adapted to be opened in order to make

the interior of the case is accessible for change of stitching needles or for other purposes.

Having thus described the invention, what is claimed as new and desired to be secured by Letters Patent is:

1. A darning-machine provided with knitting needles adapted to be moved up and down, in combination with a rotary member having stages adapted at its rotation to actuate the knitting needles to be successively moved to and from the working position.

2. A darning-machine provided with knitting needles adapted to be moved up and down, in combination with a rotary drum provided with cams, on which are stages each adapted to actuate a knitting needle at the rotation of the drum in such manner that said needles are successively moved to and from the working position.

3. A darning-machine provided with knitting needles adapted to be moved up and down, in combination with a rotary member adapted at its rotation to actuate the knitting needles to be successively moved to and from the working position, and with a feeding member adapted to be moved by means of a cam disc secured on the rotary member actuating the needles.

4. A darning-machine provided with knitting needles adapted to be moved up and down, in combination with a rotary member adapted at its rotation to actuate the knitting needles to be successively moved to and from the working position, and with a member provided with feeding needles and rockable about a shaft, which is adapted to be given a parallel movement from and to the working piece by means of a cam disc secured on the said rotary member.

5. A darning-machine provided with knitting

needles adapted to be moved up and down, in combination with a rotary member adapted at its rotation to actuate the knitting needles and with a thread guide adapted to be moved by means of a cam disc or the like secured on the said rotary member.

6. A darning-machine provided with knitting needles adapted to be moved up and down, in combination with a rotary member adapted at its rotation to actuate the knitting needles, and with a thread guide adapted to be moved by means of a cam disc or the like secured on the said rotary member, said guide being arranged on a movable arm or the like which normally is positioned just above the support for the working piece and is adapted to be moved from this position only in a certain position of the rotary member actuating the needles, in order to lay said support free for removing or inserting a working piece in the darning position.

7. A darning-machine provided with knitting needles adapted to be moved up and down, in combination with a rotary member adapted at its rotation to actuate the knitting needles to be successively moved to and from the working position and adapted to be locked in a desired position of rotation by means of an adjustable device.

8. A darning-machine provided with knitting needles adapted to be moved up and down, in combination with a rotary member adapted at its rotation to actuate the knitting needles to be successively moved to and from the working position, the axis of said rotary member having an adjustable position in order to enable the moving path of the knitting needles to be varied.

ERIK GUSTAF AHNSTRÖM.
